CHAIN-STITCH SEWING MACHINE

Andrew B. Clayton, Union, N. J., assignor to The
Singer Manufacturing Company, Elizabeth,
N. J., a corporation of New Jersey

Application February 14, 1942, Serial No. 430,854

13 Claims. (Cl. 112—200)

This invention relates to sewing machines and more particularly to sewing machines of the chain-stitch variety.

Heretofore, it has been customary, in a Singer chain-stitch sewing machine, to have the machine provided with a base-plate adapted to rest upon the upper surface of a power table and an overlying work-supporting cloth-plate supported from the base-plate and positioned approximately three inches above the upper surface of the power table. This two-level construction and arrangement rendered it difficult for the operator to support and manipulate her work and furthermore it was conducive to fatigue.

This invention therefore has as its primary object to provide an improved chain-stitch sewing machine designed to be secured within a cut-out in a power table with the upper surface of the work-supporting cloth-plate substantially flush with the upper surface of the power table, as is common in lock-stitch sewing machines.

A further object of the invention is to render available a chain-stitch sewing machine having its cloth-plate substantially flush with the power table and capable of having substantially all of its bearing surfaces lubricated automatically by oil contained within a reservoir formed in a machine-supporting base, the oil being forced to the various bearings by means of a pump and suitable pipes and ducts, as in the Singer class 241 lock-stitch sewing machine illustrated in United States patent to Kaier, No. 2,206,285, July 2, 1940.

A still further object of the invention is to provide a chain-stitch sewing machine as above described in which the entire looper mechanism and substantially all of its actuating means is carried by a bracket removably secured to the underside of the cloth-plate. This greatly facilitates manufacture as it permits all of the lubricant ducts and other holes to be drilled and all surfaces to be machined and finished before the bracket is applied to the machine, which drilling and finishing operations otherwise would be extremely difficult, if not impossible. Furthermore, the use of the removable bracket permits ready assembling of the looper mechanism and the installation, in the machine frame, of a rotary looper-actuating shaft having, intermediate its ends, a crank adapted to give to the looper-carrier the oscillatory motions which, in turn, give to the looper its loop-seizing and -shedding movements.

With the above and other objects in view, as will hereinafter appear, the invention comprises the devices, combinations and arrangements of

parts hereinafter set forth and illustrated in the accompanying drawings of a preferred embodiment of the invention, from which the several features of the invention and the advantages attained thereby will be readily understood by those skilled in the art.

In the drawings, Fig. 1 is a side elevation, partly in section, of a two-thread chain-stitch sewing machine embodying the present invention, showing the machine seated upon and within a suitable supporting base and with the upper surface of its work-supporting plate substantially flush with the upper surface of the power table.

Fig. 2 is a bottom view of the machine shown in Fig. 1.

Fig. 3 is an enlarged transverse section taken substantially on the lines 3—3 of Figs. 1 and 2.

Fig. 4 is an enlarged left end elevation, partly broken away, of the machine shown in Fig. 1 with the face-plate removed.

Fig. 5 is a detail perspective view of the removable bracket which supports the looper mechanism together with the parts carried thereby.

Fig. 6 is a detail plan view showing a portion of the work-supporting plate, looper, looper-thread guiding tube and the looper-thread take-up located between the end of the thread-guiding tube and the looper.

Fig. 7 is a vertical longitudinal section substantially on the line 7—7 of Fig. 6.

Referring more specifically to the drawings, the invention is disclosed as embodied in a two-thread chain-stitch sewing machine comprising a frame including a bed 1 affording a horizontally disposed work-supporting plate P, a standard 2, an overhanging arm 3 and a hollow head 4. The bed 1 is formed with depending end walls 1^c, 1^d and depending side walls 1^e, 1^f, to be referred to later.

Journalized lengthwise within the arm 3, in bearings 5, 5^a, 5^b is a rotary main shaft 6 adapted to be driven from any suitable source of power connected by a suitable belt (not shown) to a combined belt- and hand-wheel 7 secured upon the rear end of the shaft 6. A needle-bar 8 is reciprocably mounted in upper and lower bearing bushings 8^a and 8^b, respectively held within the head 4 and carries, at its lower end, an eye-pointed needle 9. The needle-bar is reciprocated from the main shaft 6 through the medium of a crank-disk 10 secured upon the forward end of the shaft, a crank 11 carried by the crank-disk and a link 12 connecting the crank-pin with a stud 13 carried by a collar 14 secured upon the needle-bar. A spring-depressed presser-bar 15 also is mounted

on the needle-bar 8, the presser-bar being urged into engagement with the work-supporting plate P by a spring 16.

in the head 4 and carries, at its lower end, a presser-foot 16. The forward face of the head 4 is normally closed by a removable face-plate 17.

Thread n for the needle 8 extends from a source of supply through a thread-guide 18 and thread-tension 19 secured upon the arm 3, through a second thread-guide 20 secured to the arm, thence through a take-up, comprising an arm 21, secured to the needle-bar 8, having in its free end a thread-eye 21 a , and a cooperating thread-engaging finger 22 adjustably secured upon the head 4, as by screw 23. From the thread-eye 21 a , the thread extends downwardly through a thread-guide 24 also fixed to the head 4, through another thread-guide 25 at the lower end of the needle-bar and thence to the eye of the needle.

Cooperating with the needle in the formation of stitches is a four-motioned looper mechanism including a looper L, all later to be described. Thread l for the looper extends from a source of supply, through a thread-guide 26, tension 27, thread-guiding tube 28 embedded in the work-supporting plate P, through a rotary take-up, comprising stationary thread-guides 29, a rotary take-up cam-disk 30 and a thread-stripper 31, and thence to the looper.

Journalized in bearing bushings 32, 33 and 34, of which the latter two are supported in bearing lugs 33 a and 34 a formed integral with the work-supporting plate P, is a rotary looper-actuating shaft 35, having, intermediate the bearings 32 and 33 a looper-reciprocating crank 36 and a looper vibrating eccentric 37. The take-up cam 30 is secured upon the forward end of the shaft 35 by a screw 38. The shaft 35 is rotated from the shaft 6 through the medium of a pair of bevel gears 39, 40, an upright shaft 41 journalized in the standard 2 and a second pair of bevel gears 42, 43 secured upon the shafts 41 and 35, respectively.

The machine is provided with a four-motioned feeding mechanism including a feed-bar 44 and a serrated feed-dog 45 (Fig. 4) secured thereto as by means of a screw 46. The feed-dog operates through suitable slots formed in a throat-plate 47 carried by the work-supporting plate P. The feed-bar is pivotally connected at its rear end to a feed-rocker 48 forming a part of a rock-shaft 49 journalized on pintles 50, 51 supported in lugs 50 a , 51 a depending from the work-supporting plate P. The rock-shaft 49 is oscillated on its pintle bearings, thereby to give to the feed-bar and the feed-dog carried thereby their advancing and retracting movements, by an eccentric 52 secured upon the main shaft 6. A pitman 53, within the standard 2, has at its upper end a strap which embraces the eccentric 52 while the lower end of the pitman is connected to the free end of a rock-arm 54 (Fig. 2) secured upon the rear end of the rock-shaft 49.

The forward end of the feed-bar is formed as a fork 55 which engages a block 56 pivotally mounted upon the free end of a rock-arm 57 secured upon the forward end of a second rock-shaft 58 journalized upon pintles as 56 carried by the bed 1. At its rear end the rock-shaft 58 is formed with an arm 59 to which is pivotally connected the lower end of a second pitman 60 also located in the standard 2 and having at its upper end a strap which surrounds a feed-lift eccentric 62 secured upon the main shaft 6. Thus rotation of the main shaft will, through the elements 62, 61, 60, 58, 57 and 56, effect rising and falling movements of the feed-bar 44 and the feed-dog 45 carried thereby, in timed relation with its ad-

vancing and retracting movements, as is common in four-motioned feeding mechanisms.

The looper L, hereinbefore mentioned, which cooperates with the needle in the formation of stitches, is secured to the upper end of an oscillating and laterally vibrating looper-carrier 63 having its lower end clamped, as by screw 64, upon a short rock-shaft 65 journalized in the tubular cross-head 66 of a substantially T-shaped looper-carrier support 67. The looper-carrier support includes a cylindrical tubular stem portion 68 which is journalized in bearing bushings 69 and 70 fitted within a bearing-support 71 forming a part of a bracket B which has a portion B 1 fitted within and filling a cut-out 72 formed in the end wall 1 a of the bed 1. See Fig. 3. The bracket B is removably secured upon flat seats 1 a and 1 b (see Fig. 3) formed on the underside of the bed-plate 1 as by means of screws 72 passing through holes 73 in the bracket and threaded into the plate P. The bracket B also carries the bearing 32 for the shaft 35 and all of the looper-actuating mechanism except the looper reciprocating crank 36 and the looper-vibrating eccentric 37 which are carried by the shaft 35.

The bracket B is formed with a mid-section extending crosswise of the work-supporting plate P and a pair of spaced arms b 1 and b 2 projecting from one side of the mid-section in which is secured, as by set screws b 3 and b 4 (Figs. 2 and 3), a stud 78 having a head 78 a fitted into the arm b 2 and adapted to have connected therewith a lubricant-conducting tube k 2 later to be referred to.

Oscillatory motions are transmitted to the looper-carrier 63, thereby giving the looper its endwise reciprocating loop-seizing and -shedding movements from the crank 36 on the shaft 35. This is effected through the medium of a pitman

74 having one end embracing the crank 36 and its other end embracing a ball 75 formed on an arm 76 carried by an oscillatory tubular rocker 77 journalized on the stud 78 between the arms b 1 and b 2 of the removable bracket B. The rocker 77 also is formed with an upstanding arm 79 (Fig. 5) to which is connected by a ball-and-socket joint one end 80 a of a link 80 which passes through a hole 81 in the bracket B and has its other end 80 b connected by a ball-and-socket joint with the looper-carrier 63.

Surrounding the eccentric 37, on the shaft 35, is a block 82 which is slidably fitted between the spaced arms of a fork 83 the lower end 83 a of which is clamped upon the stem 68 of the looper-carrier frame 67. Thus rotation of the shaft 35 also effects, through the elements 31, 32, 33, 38, 67 and 63, sidewise or laterally vibrating movements of the looper L.

Secured to the shank of the looper, as by screw 84 a is a needle-guide 84 which operates forwardly of the needle 8. A second needle-guide 85, adapted to engage the rear side of the needle, is supported, for universal adjustment, from the portion 71 of the bracket B. The base 85 a of the needle-guide 85 is mounted, for horizontal adjustment, on the upper end 86 a of an L-shaped bracket 86 and is held in its adjusted position by a clamp-screw 86 b . The bracket 86 is adjustably mounted, for horizontal movement transversely of the path of adjustment of the needle guide 84, on the horizontal leg 87 a of an inverted L-shaped bracket 87 which, in turn, is mounted for vertical adjustment on the portion 71 of the bracket B. Clamp screws 86 a and 87 a secure the brackets 86 and 87, respectively,

in their adjusted positions. The needle-guides 84 and 85 engage the needle and hold it against lateral deflection so that the point of the looper will not strike the needle but will always enter the thread-loop thrown out by the needle. The needle-guides will also deflect the needle into its proper position should it be bent transversely of the path of the looper.

As shown most clearly in Figs. 1 and 3, the bed 1 of the machine is mounted upon a cast-metal base A supported in an opening or cut-out t formed in a table T with the top of the work-plate P substantially flush with the top of the table. The base A serves as an oil reservoir R from which oil is conducted to substantially all of the bearing surfaces of the machine. To insure that no oil will accidentally escape from the reservoir or oil-pan the downwardly extending end walls 1^c, 1^d and side walls 1^e, 1^f of the bed and the rounded lower portion b¹³ of the bracket B rest upon gaskets g supported by the base A.

To permit the machine to be tipped backwardly for the purpose of inspection or repair, the rear edge of the bed 1 carries hinge elements 88 which engage complementary hinge elements 89 (Fig. 3) secured in the table-top T, as by bolts 90.

Located within a sump S formed at one end of the base A is an oil pump O which is operated from the shaft 41 and which draws in oil from the sump and discharges it through conduits k, k¹, k², and k³ to various parts of the machine. The conduit k extends upwardly within the standard 2 and has its upper end connected at k⁴ with the bearing 5^a of the main shaft 6. From the bearing 5^a the oil flows through a radial duct d into a longitudinal bore 6^b formed in the shaft 6 and from that bore through suitable ducts designated generally as x to the bearings 5 and 5^b, to the needle-bar actuating mechanism, to the bearing surfaces of the feed-drive and feed-lift eccentrics 52 and 62, respectively, and to the bevel gears 39 and 40. The conduit k¹ leads to the bearing 33 of the shaft 35. The conduit k² has its forward end connected with a central bore 78^b (Figs. 1 and 3) formed in the stud 78 and radial ducts leading from the bore conduct lubricant to the bearing surfaces of the stud 78 and the rocker 77 journaled thereon. The conduit k³ has its forward end connected with a bore b⁶ formed in the bracket B (Figs. 3 and 5). This bore communicates with a transverse bore b⁷, also in the bracket B, which in turn connects with a radial duct b⁸ formed in the bearing bushing 32. A portion of the oil thus transmitted to the shaft bearing surface within the bushing 32 is picked up, during rotation of the shaft 35, by the straight side wall 35^a of a radial duct 35^b and conducted to a bore 35^c formed lengthwise within the shaft 35. Oil in the bore 35^c is transmitted through suitable ducts to the bearing surfaces of the eccentric 37, crank 36 and ball 75. Other oil within the bushing 32 collects in an annular chamber 32^a in the bushing and is conducted through aligned ducts 32^b and b⁹ in the bearing bushing 32 and bracket B, respectively, and slot 70^a in the bearing bushing 70, to a chamber 71^a in the bearing support 71. From the chamber 71^a the oil flows inwardly through radial ducts to a bore 68^a formed in the stem 68 of the looper-carrier support and thence to the bearing surfaces of the cross-head 66 and rock-shaft 65 journaled therein. Any oil which escapes from the forward end of the bearing bushing 32 gravitates into a catch basin b¹⁰ formed in the bracket 75

B and is returned to the reservoir within the base A, by an inclined duct b¹¹ also formed in the bracket B. The bearings of the four-motioned feeding mechanism are lubricated from oil in the reservoir R by means of suitable oil-cup wicking, not shown.

The ball-joint connection between the link 88 and the looper-carrier 63 is lubricated by oil contained in a sump S¹ formed in the left end of the base A, through the medium of a wick w carried by a sheet-metal support w¹ secured in one end of the shaft 85. The lower end of the wick rests in the sump S¹ while the upper end thereof is maintained in contact with said ball-joint and transmits lubricant thereto by capillary action.

As shown most clearly in Fig. 4 the upper bearing 8^a of the needle-bar 8 is lubricated by oil collected in a sump 4^a formed in the lower end of the head 4. This oil is transmitted to the needle-bar bearing 8^a by a wick 8^x located in the head 4 and having one end 8^x in the sump 4^a and its other end surrounding the lower end of the bearing 8^a. Oil from the upper end of the wick passes through holes formed in the bearing 8^a to the inside thereof where it lubricates the bearing surfaces of the bearing and the needle-bar therein.

From the foregoing it will be understood that all of the bearings of the machines are lubricated constantly and automatically from lubricant contained in the reservoir R and sumps S¹ and 4^a. It will also be seen that a number of the ducts and ports which conduct the oil to the bearings of the looper mechanism are drilled in the removable bracket B. With the bracket removed from the machine the drilling of those holes may very readily be accomplished whereas such drilling operations would be decidedly difficult, if not actually impossible, to perform were the bracket formed as an integral part of the machine bed.

Having thus set forth the nature of the invention what I claim herein is:

1. A chain-stitch sewing machine comprising a frame including a bed having depending end and side walls adapted to be supported upon an oil pan carried by a suitable table with the upper face of said bed substantially flush with the upper surface of said table, one of said end walls being cut away adjacent the center of said bed, a reciprocating needle-bar carried by said frame, an eye-pointed needle carried by said needle-bar, a rotary shaft journaled in bearings supported by said bed, a bracket removably secured to the underside of said bed and having a portion filling the cut-away portion of said end wall, and a looper mechanism carried by said bracket and actuated from said shaft, said looper mechanism including a looper adapted to cooperate with said needle in the formation of stitches.

2. A two-thread chain-stitch sewing machine comprising a frame including a bed, a standard, an overhanging arm and a needle-bar supporting head, a rotary main shaft journaled lengthwise within said arm, a needle-bar mounted in said head and actuated from said shaft, a needle carried by said needle-bar, a four-motioned work-feeding mechanism including a feed-drive rock-shaft and a feed-lift rock-shaft journaled in bearings supported by said bed, feed-drive and feed-lift eccentrics carried by said main shaft, operative connections between said eccentrics and said feed-drive and feed-lift rock-shafts, respectively, a rotary driven shaft journaled in bearings supported by said bed, means for rotating said driven shaft from said main shaft, a looper mechanism mounted beneath said bed and including a

looper-carrier and a thread-carrying looper therein adapted to cooperate with said needle in the formation of stitches, and means actuated from said rotary driven shaft for giving to said looper endwise reciprocatory and lateral vibratory motions.

3. A two-thread chain-stitch sewing machine comprising a frame including a bed, a reciprocating needle-bar mounted in said frame above said bed, an eye-pointed needle carried by said needle-bar, a rotary shaft journaled in bearings supported by the underside of said bed, a bracket removably secured to the underside of said bed, a four-motioned looper mechanism carried by said bracket and actuated from said shaft, said looper mechanism including a thread-carrying looper which cooperates with said needle in the formation of stitches, and a needle-guide supported for universal adjustment on said bracket.

4. A two-thread chain-stitch sewing machine comprising a frame including a bed, an endwise reciprocating needle-bar mounted in said frame, an eye-pointed needle carried by said needle-bar, a rotary shaft journaled in bearings provided by said bed, a bracket removably secured to the underside of said bed and affording a bearing-support, a four-motioned looper mechanism carried by said bracket and actuated from said shaft, said looper mechanism including a thread-carrying looper which cooperates with said needle in the formation of stitches, and a needle-guide carried by said bracket and engaging said needle to position the needle relative to said looper.

5. A two-thread chain-stitch sewing machine as set forth in claim 4 in which the needle-guide is adjustably supported upon said bracket for both vertical and horizontal adjustment.

6. A two-thread chain-stitch sewing machine as set forth in claim 4 in which an inverted L-shaped bracket is mounted for vertical adjustment on the bearing-support; in which a second L-shaped bracket is mounted for horizontal adjustment on the horizontal arm of the inverted L-shaped bracket; and in which, the needle-guide is adjustably mounted on said second L-shaped bracket for horizontal adjustment in a path transverse to the path of adjustment of said second bracket.

7. A four-motioned looper-mechanism for cooperation with the reciprocating eye-pointed needle of a chain-stitch sewing machine having a bed and a rotary shaft journaled in bearings provided by said bed, said looper-mechanism comprising a supporting bracket removably secured upon the underside of said bed and affording a bearing-support located below and substantially parallel with said shaft, a substantially T-shaped looper-carrier support having its stem-portion journaled in said bearing-support and having a bore formed in and lengthwise of its head-portion, a looper-carrier journaled in said bore, a looper secured to said looper-carrier, means carried by said bracket and actuated from said shaft for oscillating said looper-carrier to give endwise reciprocations to said looper, and means carried by said bracket and actuated from said shaft for oscillating said looper-carrier-support to give sidewise movements to said looper-carrier and looper.

8. A four-motioned looper-mechanism for sewing machines as set forth in claim 7 in which the removable bracket is formed with a pair of spaced arms; in which the means for oscillating the looper-carrier, thereby to give the looper its endwise movements, comprises a rocker journaled

between said spaced arms and having a plurality of off-set arms; in which one arm of said rocker is connected to an eccentric element on the shaft by which oscillatory motions are transmitted to said rocker from the rotary motion of said shaft, and in which the other arm of said rocker is connected by a link to said looper-carrier.

9. A four-motioned looper-mechanism for sewing machines as set forth in claim 7 in which the stem-portion of the looper-carrier support extends through and projects beyond one end of the bearing-support provided by the removable bracket, and in which said projecting end carries a fork which embraces an eccentric element carried by said shaft, whereby oscillatory motions are transmitted to said looper-carrier support from the rotary motion of said shaft, thereby effecting the sidewise motions of said looper-carrier and looper.

10. A looper-mechanism supporting-bracket, adapted to be secured to the underside of the work-supporting plate of a sewing machine, comprising a mid-section adapted to extend crosswise of the work-supporting plate of the sewing machine, a pair of spaced arms projecting from one side of said mid-section, said arms being provided with aligned apertures and adapted to support a portion of a chain-stitch looper-actuating mechanism, and a bearing-supporting extension, projecting from the opposite side of said mid-section, adapted to support another portion of said looper-actuating mechanism, said mid-section having flat substantially horizontal upper surfaces designed to fit complementary flat seats formed on the underside of the work-supporting plate, said mid-section also being provided with vertically disposed bolt holes for the passage of bracket-attaching bolts.

11. A looper-mechanism supporting-bracket comprising a mid-section having a substantially flat upper surface adapted to be secured to a complementary flat seat on the underside of the work-supporting plate of a sewing machine, a pair of spaced arms projecting from one side of said mid-section, said arms being constructed and arranged to support a rocker element forming a portion of a chain-stitch looper-actuating mechanism for giving endwise reciprocations to a chain-stitch looper, and a bearing-supporting extension projecting from the opposite side of said mid-section and adapted to support means for giving sidewise movements to the chain-stitch looper.

12. A looper-mechanism adapted to be removably supported on the underside of the work-supporting plate of a sewing machine and operated from a rotary shaft journaled beneath said plate and having an eccentric thereon, comprising a bracket having a mid-section adapted to be secured to the underside of said work-supporting plate, a pair of spaced arms projecting from one side of said mid-section, a rocker journaled between said arms, a connection from said rocker to the eccentric on said shaft for effecting oscillations of said rocker, a bearing-supporting extension projecting from the opposite side of the mid-section, a looper-carrier-support journaled in said extension, a looper-carrier journaled in said support and carrying a looper, means actuated from said rotary shaft for oscillating said looper-carrier-support transversely of said shaft to give sidewise movements to the looper-carrier and the looper carried thereby, and a connection between said looper-carrier and said rocker for oscillating said looper-carrier lengthwise of said

shaft for giving endwise reciprocations to said looper.

13. A two-thread chain-stitch sewing machine comprising a work-supporting plate, a rotary shaft journaled in bearings beneath said plate, two eccentrics carried by said shaft, a reciprocating thread-carrying needle mounted above said plate, a looper-mechanism supporting-bracket including a mid-section removably secured to the underside of said plate, said mid-section having therein a plurality of apertures through one of which said shaft projects, a pair of spaced arms integral with and projecting from one side of said mid-section, a bearing-supporting extension integral with and projecting from the opposite side of said mid-section, a looper-carrier-frame

15 supported by said extension, a looper-carrier journaled in said frame, a thread-carrying looper supported by said looper-carrier for cooperation with said needle, a rotary looper-thread take-up disk carried by said shaft at that side of said mid-section from which said extension projects, looper-actuating elements carried by said bracket between said arms and connected with the eccentrics on said shaft, and members extending through others of said apertures in said bracket for connecting said elements with said looper-carrier-frame and looper-carrier respectively, for transmitting endwise reciprocating and laterally vibrating movements to said looper.

ANDREW B. CLAYTON.
